Primary Examiner—Mimosa De*(74) Attorney, Agent, or Firm*—Merchant & Gould PC(57) **CLAIM**

The ornamental design for a seating apparatus, as shown and described.

DESCRIPTION

FIG. 1 is a front elevational view of a seating apparatus according to the principles of the present invention;

FIG. 2 is a rear elevational view thereof;

FIG. 3 is a right side elevational view thereof, a left side elevational view not being shown as it is a mirror image of the right side elevational view;

FIG. 4 is a top plan view thereof; and,

FIG. 5 is a bottom plan view thereof.
